US0D1085230S

(12) **United States Design Patent** (10) **Patent No.:** **US D1,085,230 S**
(45) **Date of Patent:** **** Jul. 22, 2025**

(54) **PACKING TAPE DISPENSER**

(71) Applicant: **Xiaoming Wang**, Cixi (CN)

(72) Inventor: **Xiaoming Wang**, Cixi (CN)

(**) Term: **15 Years**

(21) Appl. No.: **29/824,965**

(22) Filed: **Jan. 28, 2022**

(51) **LOC (15) Cl.** **19-99**

(52) **U.S. Cl.**

USPC **D19/69**

(58) **Field of Classification Search**

USPC D19/34, 66, 67, 68, 69, 82, 86; D11/164; D8/20, 49, 367, 382, 37

CPC Y10T 156/1348; Y10T 156/1365; B65H 35/0033; B65H 35/0026

(57) **CLAIM**

The ornamental design for a packing tape dispenser, as shown and described.

DESCRIPTION

FIG. 1 is a first perspective view of a packing tape dispenser showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the packing tape dispenser that form no part of the claimed design.

1 Claim, 8 Drawing Sheets
